UNITED STATES PATENT OFFICE.

LAURENCE J. HEFFERNAN, OF NEW YORK, N. Y.

DESIGN FOR A PAPER-WEIGHT.

SPECIFICATION forming part of Design No. 21,863, dated September 20, 1892.

Application filed August 27, 1892. Serial No. 444,329. Term of patent 3½ years.

To all whom it may concern:

Be it known that I, LAURENCE J. HEFFERNAN, of New York city, in the county and State of New York, have invented a new and original Design for a Paper-Weight, of which the following is a specification.

Reference is to be had to the accompanying drawing, forming a part of this specification, the single view shown being a perspective representation of the design.

As illustrated, A represents the base of the paper-weight and is shaped as the frustum of a prismatic pyramid whereon an overhanging flat triangular tablet B is indicated. Sur-

mounting the tablet B a human head C appears, purporting to represent that of Columbus. These are the main features of the design, a minor feature consisting of a ruching D, intervening the head and tablet.

Having described my invention, I claim as new and desire to secure by Letters Patent—

The design for a paper-weight herein shown and described.

LAURENCE J. HEFFERNAN.
